ELECTRONIC STATIC DISCHARGE APPARATUS

Alex J. Check, Struthers, Ohio

Application May 14, 1948, Serial No. 26,958

2 Claims. (Cl. 317—2)

1

This invention relates to devices for discharging electrostatic fields and more particularly to a device for electronically discharging an electrostatic field.

The principal object of the invention is the provision of means for electronically discharging electrostatic fields.

A further object of the invention is the provision of means for electronically discharging electrostatic fields from fluids.

A still further object of the invention is the provision of a device for electronically discharging electrostatic fields wherein a ground circuit is established and means employed for establishing a carrier current on said circuit to facilitate the discharge of electrostatic fields therethrough.

A still further object of the invention is the provision of electronic means for removing static electricity from dry cleaning machines and more particularly from solvent circulated through a dry cleaning machine.

This invention is a continuation in part of my patent application Serial No. 790,913 on Grounding Electrode for Dry Cleaning Machines, filed December 10, 1947, which has become abandoned.

The electronic static discharge apparatus shown and described herein is particularly useful in continuously discharging static electricity from fluids such as solvents employed in dry cleaning operations and thereby preventing the redepositation of soil particles in garments being cleaned in the solvent. As is well known in the art of dry cleaning, the so-called "graying" of garments occurs periodically during the "washing" or actual dry cleaning operation and as is also known in the art the periodic "graying" of garments has been attributed to many and various causes. For example, the presence or absence of moisture in the garments and/or dry cleaning solvent has been set forth as a contributing cause by various dry cleaning authorities and the proposal heretofore made that by controlling the moisture content of the garments and/or the solvent, the incidents of "graying" might be reduced.

It is also well known that the "graying" is directly caused by the redeposition of minute soil particles in the garments in the dry cleaning machine usually subsequent to their initial removal from the garments. For example, a dry cleaning machine with new solvent charged therein and continuously circulated through a newly charged filter will become loaded with minute soil particles removed from garments placed therein and sometimes all of the soil particles will be circulated with the solvent to the filter and

2

retained thereby while at other times a majority of the soil particles will be redeposited in the garments in the dry cleaning machine despite the continuous circulation of the solvent through the machine and its associated filter.

The basic cause of the redeposition of soil is believed to lie in the creation of electrostatic filters in the dry cleaning solvent, the garments in the dry cleaning machine, in the solvent, and in the soil particles suspended in the solvent itself by the movement of the garments, the solvent and the soil particles as occasioned by the operation of the dry cleaning machine. As the phenomenon of "graying" occurs during the actual dry cleaning operation, the normal accumulation of electrostatic fields in the solvent and the soil particles therein is believed to be responsible, as by their presence in the electrostatic fields, in effect, attract the minute soil particles from their normal suspension in the solvent to the garments where they are retained with the resulting evenly distributed uniformly gray appearance.

In my co-pending patent application Serial No. 790,913, I disclose a grounding electrode and a novel positioning of the same with respect to the dry cleaning fluid for effectively grounding the electrostatic charges in the dry cleaning fluid and it has been determined by many tests that a considerable portion of the electrostatic fields created within the dry cleaning machine are removed by the simple provision of a properly formed, and more importantly, properly located grounding electrode. It has also been determined that all of the electrostatic fields created in a dry cleaning machine may be effectively removed by completely eliminating the resistance in the grounding electrode and its ground circuit through the establishment therein of a relatively small direct current flow to ground.

The present disclosure relates to this improvement and specifically to the establishment of a grounding electrode and ground circuit properly positioned in the solvent communicating with the dry cleaning machine and provided with means for establishing a carrier current directly from the grounding electrode to ground to effectively eliminate the resistance of this circuit and thereby enable the grounding of all of the static electricity generated within the dry cleaning machine, the solvent therein or the garments therein.

With the foregoing and other objects in view which will appear as the description proceeds, the invention resides in the combination and arrangement of parts and in the details of construction hereinafter described and claimed, it

being understood that changes in the precise embodiment of the invention herein disclosed can be made within the scope of what is claimed without departing from the spirit of the invention.

The invention is illustrated in the accompanying drawing, wherein:

Figure 1 is a plan view of the electronic static discharge apparatus with parts in cross section and parts broken away.

Figure 2 is a diagrammatic illustration of the electronic static discharge apparatus.

Figure 3 is a plan view of a preferred form of mounting of the electronic static discharge apparatus on a dry cleaning machine.

Figure 4 is a plan form of mounting of the electronic static discharge apparatus on the dry cleaning machine.

By referring to the drawings and Figures 1 and 2 in particular it will be seen that an explosion-proof box 10 has been illustrated in cross section and that it partially encloses an end 11 of a grounding electrode 12, the majority of the grounding electrode 12 extending outwardly beyond the exterior of the explosion-proof box 10 and adapted for mounting within a fitting such as a T 13 through which dry cleaning solvent may be circulated. Disposed within the explosion-proof box 10 there is a unit 14 comprising, as may be seen by referring to Figure 2 of the drawings, a transformer including a primary winding 15 and a secondary winding 16. The secondary winding 16 of the transformer is in electrical connection with a rectifier which may be either full wave or half wave, as desired, the full wave being preferred, and a condenser 18 connected across the terminals of the rectifier 17.

A power supply for the primary winding 15 of the transformer comprises a pair of circuit wires 19 and are adapted to be connected to a 110 volt A. C. circuit. The secondary winding 16 of the transformer provides 3 volts A. C. which is converted by the rectifier 17 to 3 volts D. C. The positive terminal of the rectifier is connected by means of a circuit wire 20 with a tap 21 on the end 11 of the grounding electrode 12 and a circuit wire 22 connected with the negative terminal of the rectifier 17 and with a resistance unit of approximately 200,000 ohms indicated in the drawing by the numeral 23. The resistance unit 23 is connected by a circuit wire 24 with a ground tap 25 which comprises a screw-like body member 26 threadably engaging an orifice in the explosion-proof box 10. A ground wire 27 establishes connection between the ground tap 25 and the ground. A circuit wire 28 connects with the ground tap 25 and with a tap 29 on the end 11 of the grounding electrode 12 and inwardly with respect to the tap 21 herefore described.

It will thus be seen that when the primary winding 15 of the transformer in the unit 14 is energized as by connection with a 110 volt A. C. power source, 3 volts A. C. will be obtained from the secondary winding 16 thereof. The rectifier 17 connected with the secondary winding 16 of the transformer converts the 3 volt A. C. to 3 volt D. C. and the positive tap terminal of the rectifier 17 is connected directly to the tap 21 on the grounding electrode 12. Thus, a positive charge is imparted to the electrode 12 and at the same time the electrode 12 is grounded by means of the circuit wire 28 connecting with the tap 29 on the electrode 12 and with the

ground by way of the tap 25 and ground wire 27. A continuous electric potential is thereby established and a continuous uninterrupted direct flow to ground obtained which greatly facilitates the collective action of the electrode 12 with respect to electrostatic fields within the dry cleaning solvent circulated thereover and soil particles therein as well as garments therein.

By referring now to Figure 3 of the drawings the preferred manner of installation of the static discharge device will be seen and it will be observed that a lower corner portion of a dry cleaning machine is indicated by the numeral 30, the solvent therein by the numeral 31 and a fitting 32 establishing communication with the machine 30 so that the solvent 31 may flow outwardly therethrough as indicated by the arrow. A T fitting 33 is connected with the fitting 32 and forms a portion of the normal communication channel between the dry cleaning machine and the filter (not shown). The directional flow of the solvent through the T fitting 33 is indicated by the arrows. The grounding electrode 12 is shown in position in the T fitting 33 and extending into the flow of the solvent therethrough.

In Figure 4 of the drawings an alternate method of installation is illustrated wherein the explosion-proof box 10 with the projecting grounding electrode 12 thereon is shown applied to a straight line type of connection between a dry cleaning machine (not shown) and a filter therefor (not shown). The tubular line communicating with the dry cleaning machine and the filter is indicated by the numeral 34 and the T therein by the numeral 35. The grounding electrode 12 is positioned within the T so that the fluid flowing within the line 34 and the T 35 will pass thereabout. The direction of flow through the T 35 is indicated by the arrows.

It has been determined that the device and particularly the grounding electrode 12 should be located within the solvent flow at a point immediately adjacent a dry cleaning machine proper and the installation illustrated in Figure 3 of the drawings is therefore preferred.

By referring again to Figure 1 of the drawings it will be observed that as is customary with explosion-proof box mountings, the grounding electrode 12 is arranged so that a portion thereof having a threaded pattern 36 formed thereon threadably engages a bushing 37 which in turn is engaged in the threaded orifice in the explosion-proof box 10. In order that the explosion-proof box and the devices therein may be carried directly on the T fitting 13 and hence on the dry cleaning machine, a secondary bushing 38 is threaded on the bushing 37 and threadably engaged in the T fitting 13. Similar threaded connections are employed in connection with a conduit 39 enclosing the circuit wires 19 by means of which the power supply is connected to the device.

It will thus be seen that a simple electronic device has been disclosed which through its ability to eliminate resistance in a ground circuit enables all of the electrostatic charges generated in a dry cleaning machine to be discharged continually and thereby prevents the development of any electrostatic potential in the machine, the solvents therein or the garments therein, which electrostatic potential, if allowed to exist, would result in the immediate redeposition of soil in the garments resulting in the phenomenon known in the dry cleaning art as "graying."

The invention disclosed herein thereby elimi-

inates "graying" and additionally eliminates the necessity of adding moisture to the liquid soaps commonly employed in connection with liquid solvents as well as the necessity of adding moisture to the garments as by humidifying cabinets as sometimes practiced in the art.

Additionally, the invention enables a satisfactory dry cleaning operation to be accomplished whereby the garments cleaned will be bright and of true color and completely free of redeposited soil to the end that the actual dry cleaning operation may be effected in considerably less time than has heretofore been believed necessary.

Having thus described my invention, what I claim is:

1. Static discharge apparatus comprising a rod-like collecting electrode, a power source and a ground, one end of the said electrode connected to said ground, a transformer in connection with the said power source and a rectifier in connection with the secondary of the said transformer, and a conductor connecting the said positive side of said rectifier with the said electrode at a point thereon spaced with respect to said ground connection and hence with the said ground by way of said electrode.

2. Static discharge apparatus comprising an

elongated collecting electrode, a power source and a ground, one end of the said electrode connected to said ground, a transformer in connection with the said power source and a rectifier in connection with the secondary of the said transformer, and means connecting the said positive side of said rectifier with the said electrode at a point spaced with respect to said ground connection thereon with the said ground through said electrode, and means connecting the negative side of the said rectifier to said ground, said means incorporating a resistance element of approximately 200,000 ohms.

ALEX J. CHECK.
